AKOS J. HALL, OF CLEVELAND, OHIO.

STAIR AND PLATFORM STRUCTURE.

Application filed December 22, 1924. Serial No. 757,367.

My invention relates to the construction of stairs and platforms generally and to connecting and supporting means therefor particularly.

5 One of the objects of my invention is a simple and easily installed stair and platform structure.

Another object is to reduce the cost of production as well as the cost of installation of such structures by arranging the elements thereof so that most of the work thereon can be performed in the shop, thereby leaving as little as possible of the work to be done in the field.

10 Another object is to reduce the cost of production of such structures by simplifying the members and the joints thereof.

Another object is a stair and platform structure in which the platform can be anchored in a wall and the stair structure adjusted thereon to suit the conditions of the building.

20 Another object is to simplify the connections between the members of such structures so that as little as possible field work is required to install these structures and so that as few as possible bolts or rivets or other similar expediencies are required to install such structures.

25 Another object is to simplify the connections between the platform and the posts and the stair stringers.

In former stair and platform structures, one of the important items is the cost of the 30 field work for installing such structures.

Usually, the shop work of such structures is fairly accurate so that such structures would assemble easily in the field if the buildings were also fairly accurate.

35 Usually, a building can not be erected as accurately as the stair and platform details can be made in the shop; the walls may be out of square, or not parallel, or the height of the anchor holes from the floor above or 40 below may not be correct; in short, it is practically impossible to construct a building as accurately as the stair and platform details.

45 Therefore, with the former stair and platform structures, considerable fitting was required when such structures were assembled in the field or installed in a building, thereby consuming much time and expense.

The present invention aims to eliminate this consumption of time and expense by 55 providing a stair and platform structure which can be installed almost anywhere, within reason, which is accomplished by arranging the members thereof so that they can be adjusted to the conditions found in 60 buildings or otherwise without fitting or other time consuming operations, by merely locating the starting or first installed member as best suits the building, then attaching the other members thereto and locating 65 them thereon, and then clamping the whole structure together.

My invention is illustrated in the accompanying drawing in which:—

Fig. 1 is a general perspective view of a 70 stair and platform structure embodying the features of my invention and showing a stairway and a portion of a platform supported in a wall and also showing the neat appearance caused by the absence of bolt or 75 rivet heads on the outside of the structure.

Fig. 2 is a sectional perspective view showing a portion of a post and the support beam passing therethrough and the clamp means for clamping the support beam to the post. 80

Fig. 3 is a plan view of the central portion of Fig. 1 showing the front portion of the platform and the relation thereto of the posts and the support beam and the stair stringers. 85

Fig. 4 is a partial section, taken on a vertical plane indicated by the line 4 in Fig. 3, showing the notch and the ear on the upper end of the stringers and the relation of these ends to the support beam. 90

Fig. 5 is a partial section, taken on a vertical plane indicated by the line 5 in Fig. 3, showing the notch and the ear on the lower ends of the stair stringers and the relation of these ends to the support beam. 95

Fig. 6 is a sectional view, taken on a horizontal plane indicated by the line 6 in Figs. 4 and 5, showing more clearly the manner of securing the stair stringers to the posts.

Fig. 7 is a partial section of the lower 100 ends of the lower posts, taken on a vertical plane indicated by the line 7 in Fig. 1, showing the notch and the ear on the bottom of the lower stair stringers and the relation of these lower ends to the posts.

Fig. 8 is a partial section, taken on a hori-

zontal plane indicated by the line 8 in Fig. 7, showing the manner of securing the lower ends of the stringers to the bottom posts.

Fig. 9 is a sectional perspective view showing the typical connection between the tread and risers and the stringers.

Similar reference characters refer to similar parts throughout the views.

The structure shown in the accompanying drawing comprises, principally, the platform A (shown partly only), the lower stair unit B (shown fully), the upper stair unit C (also shown partly only), the middle post D, the end posts E and F, and the lower posts G and H.

The platform may have any suitable frame upon which the floor 10 is supported. Any or all of these frame members may be anchored in or on a wall. For present purposes it is necessary to refer to only one of these frame members, the beam 11, the ends 12 of which are anchored in the walls 13 and 14 respectively.

The middle post D is hollow and has the openings 15 through the walls 16 and 17 thereof to permit the beam 11 to pass through this post, or in other words, permit the post D to be slipped onto the beam 11 and to be moved thereon to adjust the same thereon into desired position.

For the purpose of economy of manufacture, I prefer to make the openings 15 a little larger than the sectional outline of the beam 11 so that this post can be slipped over the beam 11 readily and without fitting. The walls 19 of the openings 15 are flush with the inside of the wall 18 so that the back of the beam 11 bears thereon when the post D is clamped thereon. The walls 20 of the openings 15 rest on the top of the beam 11, thereby supporting the post D on the beam 11 vertically.

As seen in Fig. 2, the back of the beam 11 bears on the wall 18 of the post D and this post is supported vertically on the top of the beam 11. In order to retain this post D in desired longitudinal position on the beam 11, I provide the clamp J having the portion 21 to engage the ends of the flanges of the beam 11 and the portions 22 bearing against the inside of the wall 18. The bolts 23 pass through the wall 18 and through the portions 22 and, upon tightening thereof, securely clamp the post D laterally onto the beam 11.

The posts E and F are similar to the post D, are supported on the beam 11 in the same manner as the post D, and are clamped to the beam 11 in the same manner as the post D, therefore, I have designated the corresponding portions of the posts E and F by the same reference characters as the post D.

The lower stair unit is composed of the

stringers 24 and 25 and the treads 26 and 65 the risers 27.

The upper stair unit is composed of the stringers 28 and 29 and the treads 30 and the risers 31.

In the present instance, each of the stair units is held into a unit by the lugs 32 formed on the ends of all of the treads and risers and passing through openings in the webs of the stringers and bent against the inside of these webs as illustrated in Fig. 9. 75

As seen in Figs. 1, 4, and 5, the wall 18 of the post D has the openings 33 and 34 and that the upper end of the stringer 24 passes through the opening 33 and extends into the interior or hollow of the post D and 80 that the lower end of the stringer 29 passes through the opening 34 and also extends into the interior or hollow of the post D.

The posts E and F are similar to the post D except that only one stringer enters each 85 post; therefore, I have designated the corresponding portions of these posts by the same reference characters as the post D.

As seen in Fig. 4, the upper end of each of the stringers 24 and 25 has the notch 35 90 leaving the ear 36 by means of which these upper ends are supported on the beam 11.

The inner walls 37 of the openings 33 and 34 are flush with the inside of the walls 16 and 17 so that the ears 36 bear on these 95 walls.

The upper ends of the stringers 24 and 25 are secured to the respective sides of the posts by the bolts 38 which pass through the ears 36 and through the walls 16 or 17. 100

As seen in Fig. 5, the lower end of each of the stringers 28 and 29 has the notch 39 leaving the ear 40 which abuts the top of the beam 11; thereby supporting the stringers 28 and 29 on the beam 11. The 105 ears 40 are secured to the walls 16 or 17 by the bolts 38 similar to the ears 36.

The posts G and H are similar, each is hollow and has the walls 41 and 42. The wall 41 is provided with the opening 43 110 having the wall 44 thereof flush with the inside of the wall 42.

The lower end of each stringer 24 and 25 has the notch 45 leaving the ear 46 which extends into the interior or hollow of the posts G or H and is secured to the wall 42 by the bolt 38. The notched portion 45 abuts the walls 41 and 47 of the opening 43, thereby, augmented by the bolts 38 at this end, supporting the lower end of the stringers 24 and 25 on the posts G and H. 115

A platform or landing similar to the platform A is provided at the upper end of the stringers 28 and 29 similar to the installation of the upper end of the stringers 24 and 25 on the platform A. 125

With the present invention, the stair and platform units can be made and assembled

completely in the shop and moved into the field and placed in position there.

When the platform is in position in the building according to provisions made in the building for such position, the posts are loose on the beam 11 and can be moved thereon longitudinally of the beam. The ends of the stringers of the stair units are then inserted into the respective openings in the posts whereupon each stair unit and posts connected thereon is moved laterally on the beam 11 to adjust the stair units in relation to the walls of the building. After the stair units are so adjusted, the bolts 23 and 38 are tightened, thereby assembling or installing the stair and platform members into a rigid structure without fitting or other time consuming operations and locating the structure in desired relation to the walls of the building.

The posts G and H can be embedded in the floor as shown in Fig. 1, or may rest on the top of the floor, or may have flanges or other resting or anchoring means.

The structure shown and described is very simple and therefore economical of manufacture; the individual units of the structure are made complete in the shop which also is economical; the individual units are moved into the field and there assembled without fitting or other time consuming operations, thereby reducing the cost of installation; the units are adjustable in relation to the building, thereby further reducing the cost of installation; and the units are rigidly secured in position by merely tightening a few bolts, thereby further reducing the cost of installation.

The accompanying drawing shows one embodiment of my invention; I am aware that my invention can be embodied in other forms or in other combinations of elements and that modifications may be made within the scope of the appended claims; therefore, without limiting myself to the precise construction and arrangement shown and described, I claim:—

1. A structure of the character described, comprising, a platform, connecting mechanism slidable laterally on said platform, a stair structure resting on said platform and attached to said connecting mechanism and movable therewith, and means for clamping said connecting mechanism to said platform.

2. A structure of the character described, comprising, a platform, posts resting on said platform and laterally slidable thereon, a stair structure having one end thereof resting on said platform and attached to said posts, and said stair structure movable with said posts to permit of adjustment thereof in relation to said platform and to structure adjacent to said stair structure.

3. A structure of the character described,

comprising, a platform having beams, posts supported on one of said beams, a stair structure having stringers, each of said stringers notched to form ears resting on said one beam, each of said ears secured to the respective one of said posts, and said posts adjustable laterally on said one beam while said stair structure is being associated with said platform.

4. A structure of the character described, comprising, a platform having beams, posts supported on one of said beams, a stair structure having stringers provided with openings through the webs thereof, each of said stringers notched to form ears resting on said one beam, tread and riser sections between said stringers, lugs on said tread and riser sections and extending through said openings and bent against the web of said stringers to form a unitary stair structure, said posts adjustable laterally on said one beam while said stair structure is being associated with said platform, and said ears secured to the respective one of said posts.

5. A structure of the character described, comprising, a platform, a stair structure associated with said platform, posts fixed to the ends of said stair structure, the posts on one end of said stair structure resting on said platform and adapted to move laterally thereon to permit of lateral adjustment of said stair structure in relation to said platform and to structure adjacent to said stair structure, and the posts on the other end of said stair structure fixed in position to retain said stair structure in adjusted position.

6. A structure of the character described, comprising, a platform having a stair supporting beam, and a stair structure comprising a pair of stringers having openings through the webs thereof and notches in the ends thereof to form ears, tread and riser sections between said stringers, lugs on said sections and extending through said openings and bent against the webs of said stringers to form a unitary stair structure, said ears resting on said beam to support said stair structure vertically, and said ears secured to said platform to prevent lateral movement of said stair structure on said platform.

7. A structure of the character described, comprising, a platform having a stair supporting beam, a stair structure having stringers, and treads and risers between them an ear on one end of each of said stringers, and each of said ears resting on said beam free of lateral confinement thereon.

8. A structure of the character described, including, a stair structure having stringers, and treads and risers between them, one end of each of said stringers having a seat, each

of said seats resting on a stair support vertically to support one end of said stair structure and each of said seats slidable laterally on said chair support to permit of lateral adjustment of said stair structure in relation to the stair support and to structure adjacent to said stair structure.

9. A stair structure including, a pair of stringers, a hollow post on the lower end of each of said stringers, the lower end of each of said stringers having a seat abutting one of the walls of the hollow post thereon, and the lower end of each of said stringers having an ear extending through said one wall and secured to the wall adjacent to said one wall.

10. A stair structure including, a pair of stringers, a hollow post on each end of each of said stringers, each end of each of said stringers having a seat and an ear, each of said seats on one end of said stringers resting on a stair support means vertically, and each of said ears extending through one of the walls of the post on the corresponding end of the stringers and secured to the wall adjacent to this one wall.

11. A structure of the character described, comprising, a platform and a lower stair unit and an upper stair unit associated therewith, each of said stair units having stringers, three hollow posts supported on said platform, the upper ends of said stringers of the lower stair unit resting on said platform, the lower ends of said stringers of the upper stair unit resting on said platform, the upper end of one of said stringers of the lower stair unit and the lower end of one of said stringers of the upper stair unit extending through one of the walls of the middle one of said posts and secured to the walls adjacent to this wall, the upper end of the other of said stringers of the lower stair unit extending through one of the walls of one of the end posts and secured to the wall adjacent to this one wall, and the lower end of the other of said stringers of the upper stair unit extending through one of the walls of the other of the end posts and secured to the wall adjacent to this one wall.

12. A structure of the character de-

scribed, comprising, a platform and a stair structure associated therewith, posts connecting said platform and said stair structure, said platform having a beam extending through all of said posts, each of said posts slidable laterally on said beam, said stair structure secured to said posts and slid-
55 able laterally with said posts to permit of lateral adjustment of stair structure in relation to said platform and to structure adjacent to said stair structure, and clamp means to clamp said posts to said beam in adjusted position.

13. A structure of the character de-
65 scribed, comprising in combination, a plat-
form and a stair structure associated there-
with, posts connecting said platform and
said stair structure, said platform having
a beam extending through all of said posts,
70 each of said posts slidable laterally on said
beam, said stair structure including string-
ers having openings through the webs there-
of, tread and riser sections between said
75 stringers, lugs on said tread and riser sec-
tions and extending through said openings
and bent against said webs to form a unitary
stair structure, the ends of said stringers se-
cured to said posts and slidable laterally
80 with said posts to permit of lateral adjust-
ment of the unitary stair structure in rela-
tion to said platform and to structure adja-
cent to said stair structure, and clamp means
to clamp said posts to said beam in adjusted
position.

14. A structure of the character de-
95 scribed, comprising, a platform having a
beam and a stair structure associated there-
with, posts supported on said beam and slid-
able thereon laterally, said stair structure
90 secured to said posts and slidable therewith
to permit of lateral adjustment of said stair
structure in relation to said platform and to
structure adjacent to said stair structure, a
clamp associated with each of said posts,
95 each of said clamps embracing said beam
traversely, and bolts to secure each of said
clamps to the post thereof and thereby
clamp said posts to said beam in adjusted
position.
